UNITED STATES PATENT OFFICE.

PAUL SZUHÁNSKÝ, OF NIAGARA FALLS, ONTARIO, CANADA.

FOLDING BENCH.

Application filed January 4, 1927. Serial No. 158,915.

This invention relates to certain new and useful improvements in folding benches of that kind usually employed upon lawns and the like.

5 The primary object of the invention is to provide a folding bench which is extremely simple and durable in construction and may be readily set up for use or folded in compact condition to be conveniently stored 10 away in a comparatively small space when not required for use.

More particularly, the invention contemplates the provision of an improved folding bench embodying pivoted crossed legs and 15 a back rigid with the front legs including rigid slat carrying extensions upon the upper ends of the front legs, the slats of the back being fastened to the forward edges of the front leg extensions and projecting beyond 20 the end ones of the latter, and a seat bottom including slat supporting bars hinged at their forward ends to the upper forward ends of the rear legs and slidably associated at their rear ends with the front leg extensions, the slats of the seat bottom projecting 25 beyond the end ones of the seat bottom supporting bars in position to flatly engage the front edges of the front leg back extensions to limit the folding movement of the parts 30 to a flush compact relation.

Other objects will become apparent as the nature of the invention is better understood, and the same consists in the novel form, combination and arrangement of parts herein- 35 after more fully described, shown in the accompanying drawings and claimed.

In the drawings, wherein like reference characters indicate corresponding parts throughout the several views,

40 Figure 1 is a front perspective view of a bench constructed in accordance with the present invention and set up for use;

Figure 2 is a rear perspective view thereof;

45 Figure 3 is a rear perspective view of the bench in folded condition;

Figure 4 is a front perspective view of the folded bench shown in Figure 3.

Referring more in detail to the drawings, 50 the present invention embodies four pairs of front and rear legs 5 and 6, respectively, which are crossed and pivotally connected intermediate their ends as at 7, upon aligned horizontal axes, the rear legs 6 associated 55 with the end front legs 5 being disposed at the inner sides of the latter, and the rear

legs 6 associated with the intermediate front legs 5 being disposed at the outer sides of said intermediate front legs.

The front legs 5 are provided at their 60 upper ends with rigid extensions 8 across the front edges of the upper end portions of which are secured a plurality of slightly spaced slats 9 which project beyond the end front leg extensions and cooperate with said 65 front leg extensions to form a back rigid with the front legs.

The bench further embodies a seat bottom composed of a plurality of supporting bars 10 hinged at their forward ends as at 11 to 70 the forward upper ends of the rear legs 6, one bar 10 being pivoted to each leg 6. As shown, the bars 10 pivoted to the end legs 6 are disposed at the inner sides of the latter, while the bars 10 pivoted to the intermediate 75 legs 6 are arranged at the outer sides of said intermediate legs 5. The seat bottom of the bench further includes a plurality of slightly spaced parallel slats 12 secured across the upper edges of the supporting 80 bars 10 and extending beyond the end ones of the latter so as to flatly engage the forward edges of the leg extensions 8 when the seat bottom is swung upwardly in the folding operation of the bench, as 85 illustrated in Figures 3 and 4. In this folded condition the rearmost slat 12 of the seat bottom lies adjacent and under the lowermost slat 9 of the back, and the folding movement of the legs 6 is effectively limited 90 so that the same are aligned with the bars 10 coincident with the legs 5 and their extensions 8. Moreover, the structure is effectively braced when folded and the folding movement of the parts is further properly 95 limited by having the rear ends of the bars 10 project rearwardly beyond the rearmost slat 12 so that said projecting ends of the bars 10 engage the rear surface of the lowermost back slat 9 when the bench is in folded 100 condition, as illustrated in Figure 3.

In order to cause the proper upward swinging movement of the seat bottom of the bench when the latter is folded, a horizontal rigid guide bar 13 is provided, which 105 extends through and is tightly fitted in aligned openings provided in the rear ends of the supporting bars 10 as indicated at 14, and this bar extends through longitudinal elongated slots 15 in the intermediate 110 one of the front leg extensions 8, while the ends of the bar 13 project beyond the outer

sides of the end ones of the bars 10 and slidably engage in longitudinally elongated straight grooves 16 provided in the inner sides of the extensions 8 on the end front legs 5. The slots 15 and grooves 16 extend upwardly for a distance slightly greater than the extreme upward limit of movement of bar 13, so as to permit the before mentioned flat engagement of the slats 10 12 with the front edges of the extensions 8 when the bench is folded, thereby permitting, with assurity, the complete compact folding movement of the parts and the action of the slats 12 in conjunction with 15 the extensions 8 for limiting the folding movement. When the bench is set up for use, the lower ends of the legs 5 and 6 will flatly engage the ground, the same being suitably beveled, as shown, for this purpose, 20 and the rod 13 will engage the lower ends of the slots 15 and grooves 16 so as to properly support the bench seat bottom at its rear edge, at this time. Naturally, the opening movement of the legs 5 and 6 is 25 properly limited by the engagement of the rod 13 in the slots 15 and grooves 16, and the forward portion of the bench bottom is accordingly supported by its connection with the rear legs 6 at 11, when the bench is 30 set up for use.

Each end rear leg 6 is rigidly connected with the adjacent intermediate rear leg 6 adjacent the upper and lower ends of said legs by co-planar horizontal brace bars 17, 35 and the front legs 5 are rigidly connected adjacent their lower ends by means of a brace bar 18 which is secured across the forward edges of the legs 5 in position to engage the forward edges of the rear legs 6 when the bench is folded to aid the seat 40 slats 12 in limiting the folding movement of the parts.

From the foregoing description it will be

seen that the present bench is of a most simple and inexpensive nature, may be readily set up for use or folded in very compact condition, and will not be readily damaged when in its folded condition, because of the arrangement of the slats 9 and 12 and brace bar 18 and their cooperation with the legs, 45 leg extensions and supporting bars 10.

Minor changes may be made without departing from the spirit and scope of the invention as claimed.

What I claim as new is:—

A folding bench comprising end and intermediate pairs of crossed front and rear legs pivotally connected upon aligned horizontal axes, the front legs having co-extensive integral extensions at their upper ends, 60 horizontal slats secured across the front edges of the upper end portions of said extensions to form a back, supporting bars pivoted at their forward ends to the forward upper ends of the rear legs, parallel slats secured across the upper edges of said supporting bars to form a seat bottom and adapted to engage the front edges of the leg extensions below the first named slats when the bench is folded with the legs and 65 the supporting bars in side by side parallel relation, means pivotally and slidably connecting the rear ends of the supporting bars to said leg extensions, the intermediate rear legs being arranged at the outer sides of the 70 intermediate front legs and having their associated supporting bars arranged at the outer sides thereof, the end rear legs being arranged at the inner sides of the end front legs and having their associated supporting 75 bars arranged at the inner sides thereof, and co-planar horizontal brace bars rigidly connecting the rear legs in pairs.

In testimony whereof I affix my signature.

PAUL SZUHÁNSKÝ.
